[57] CLAIM

The ornamental design for a vacuum cleaner brush, as shown and described.

DESCRIPTION

FIG. 1 is a reduced perspective view of a vacuum cleaner brush showing our new design;

FIG. 2 is an enlarged left side elevational view thereof;

FIG. 3 is a right side elevational view thereof;

FIG. 4 is a top plan view thereof;

FIG. 5 is a bottom plan view thereof;

FIG. 6 is a front elevational view thereof; and

FIG. 7 is a rear elevational view thereof.

The vacuum cleaner shown in broken lines in FIG. 1 is for illustrative purposes only and forms no part of the claimed design.
